UNITED STATES PATENT OFFICE

2,068,573

MINING MACHINE

Leon E. Simmons, Claremont, N. H., assignor to
 Sullivan Machinery Company, a corporation of
 Massachusetts

Application May 8, 1933, Serial No. 669,952

22 Claims. (Cl. 262—30)

This invention relates to mining machines, and more particularly to improvements in the feeding means of a coal mining machine of the flexibly fed, continuous cutter, bottom cutting type.

An object of this invention is to provide an improved coal mining machine. Another object is to provide an improved mining machine feeding means. A further object is to provide an improved feeding means for a mining machine of the flexibly fed, continuous cutter, bottom cutting type. Still another object is to provide an improved feeding means for a room and pillar type mining machine whereby the machine may be fed and guided in an improved manner. A still further object is to provide an improved mining machine feeding mechanism wherein a plurality of feed operating and controlling or haulage drums are employed and having improved variable speed driving means therefor whereby the haulage drums may be driven at any desired low speed between zero and a predetermined maximum low speed. Yet another object is to provide in a feeding mechanism of the above character an improved drum driving means wherein the haulage drums may be driven at variable low speeds and at a predetermined high speed. These and other objects and advantages of the invention will, however, hereinafter more fully appear.

In the accompanying drawings there are shown for purposes of illustration two forms which the invention may assume in practice.

In these drawings,

Fig. 1 is a plan view of a mining machine of the room and pillar type having embodied therein the preferred illustrative form of the improved feeding means.

Fig. 2 is an enlarged plan view of the feeding means shown in Fig. 1, with the cover plate removed and parts shown in horizontal section to show structural details.

Fig. 3 is a central longitudinally extending vertical sectional view taken substantially on line 3—3 of Figs. 1 and 2.

Fig. 4 is a cross sectional view taken substantially on line 4—4 of Figs. 1 and 2.

Fig. 5 is a detail sectional view taken on line 5—5 of Fig. 2.

Fig. 6 is a detail sectional view taken on line 6—6 of Fig. 2.

Fig. 7 is a detail sectional view taken on line 7—7 of Fig. 2.

Fig. 8 is a view similar to Fig. 2 showing a modified form of feeding means.

Fig. 9 is a longitudinally extending vertical sectional view taken substantially on line 9—9 of Fig. 8.

Fig. 10 is a cross sectional view taken on line 10—10 of Fig. 8.

Fig. 11 is a detail sectional view taken on line 11—11 of Fig. 8.

Fig. 12 is a detail sectional view taken on line 12—12 of Fig. 8.

Fig. 13 is a detail sectional view taken on line 13—13 of Fig. 8.

As shown in Fig. 1 of the drawings, both forms of the improved feeding means are shown embodied in a mining machine of the room and pillar, continuous cutter, bottom cutting type generally designated 1, comprising a casing 2 having a plane bottom surface 3 upon which the machine is adapted to rest and slide in any direction over the mine floor. Projecting forwardly from the machine casing is a cutter bar 4 having mounted on its margin for circulation thereabout an endless cutter chain 5. Formed longitudinally through the bottom portion of the machine casing is a passage 6 through which the cutter chain moves, the rapidly moving cutter chain clearing the cuttings from the kerf and conveying them rearwardly through the bottom of the machine to discharge at the rear end of the machine in the manner usual in mining machines of the room and pillar type.

Mounted on the machine casing at the forward end thereof above the cutter bar is a motor casing 7 housing a motor, herein preferably of the reversible electric type, having its power shaft 8 horizontally disposed and extending longitudinally of the machine. Mounted within the feed frame 9 at the rear of the motor casing is a plurality of feed operating and controlling members, herein in the form of feeding and controlling or haulage drums 10 and 11, arranged in an improved manner on parallel vertical axes within the rear portion of the machine casing and respectively cooperating with feed operating and controlling elements, herein ropes or cables 12 and 13. Arranged at the opposite front corners of the machine casing are swing arms 14, 14 carrying usual guide sheaves 15, 15 for guiding the feed cable laterally from the opposite front corners of the machine during cutting in opposite directions. As shown in Fig. 1, the feeding and controlling cables are arranged to effect feed of the machine from right to left. When it is desired to effect cutting in the opposite direction, the feeding and controlling cables are arranged in the opposite manner, the cutter bits

turned in their respective links of the cutter chain and the driving motor reversed. As the room and pillar type of machine disclosed herein is generally of a standard design, and as the 5 improved feeding means may be embodied in mining machines of various other types, further description thereof is deemed unnecessary.

Now referring to the preferred form of the improved feeding means and more particularly to 10 the improved driving means for the feed operating and controlling drums, it will be noted that the power shaft 8 of the motor extends longitudinally of and is suitably journaled within the feed frame 9 and has keyed thereto at its rear 15 end a spur pinion 17 meshing with a spur gear 18 keyed to the rear end of a longitudinally extending shaft 19 herein arranged parallel with and below the motor shaft 8 and likewise suitably journaled within the feed frame 9. Keyed 20 to the forward end of the shaft 19 is a bevel pinion 20 meshing with a bevel gear 21 having its hub keyed at 22 to a vertical shaft 23. The shaft 23 is journaled within bearing sleeves 24, 25 supported within the machine casing. Journaled on a bearing sleeve 25 supported on the hub of the bevel gear 21 is a chain sprocket 26 and this sprocket is connectible to the gear 21 for driving thereby by means of a pin clutch 27 operated by a shipper member 28 having a suitable 30 controlling handle 29. The chain sprocket 26 engages and drives the cutter chain 5 in the usual manner. Formed on the upper end of the vertical shaft 23 is a bevel pinion 30 meshing with a bevel gear 31 journaled on a bearing sleeve 32 supported by a tubular shaft 33 rotatably mounted on the shaft 8. Keyed to the shaft 19 adjacent the gear 18 is a spur pinion 34 meshing with a spur gear 35 journaled on a tubular shaft 36 in turn rotatably mounted on 35 the shaft 8. The gears 31 and 35 herein respectively constitute low and high speed terminal driving gears, and are connectible to the tubular shafts 33 and 36, by multiple disc clutches 37 and 38, respectively. The improved operating 40 means for these clutches will later be described. In this instance the shafts 33 and 36 are clutched at their inner ends to the opposite hubs of a worm 39 rotatably mounted on the shaft 8 and meshing, at its opposite sides, with worm wheels 40 and 41. These worm wheels are suitably rotatably mounted on vertical shafts 42 and 43, respectively, herein arranged equidistantly from the longitudinal vertical center of the machine and suitably journaled within the feed frame 9, 45 as shown in Fig. 4. These worm wheels are connectible to the vertical shafts 42 and 43 by multiple disc clutches 44 and 45, respectively, each having suitable operating means including a pressure plate 46 engaged by a shipper yoke 47 keyed to a longitudinally extending operating shaft 48. Secured to the outer ends of these 50 shafts are suitable operating handles 49 and 50, respectively, whereby the clutches may be independently controlled. Keyed to the lower ends 55 of these vertical shafts are the feed operating and controlling drums 10 and 11 herein arranged within horizontal chambers 51 and 52 formed in the feed frame directly above the cutter chain passage 6, these chambers opening outwardly 60 through the sides of the feed frame to enable the feeding and controlling cables to be extended in various directions from their respective drums.

Now referring to the improved operating means for the speed controlling clutches 37 and 75 38, and more particularly to the improved oper-

ating means for the clutch 37 controlling the low speed terminal gear 31, it will be noted that formed on the bevel gear 31 is a sleeve portion 53, in turn having formed on its rearward edge a cam surface 54 which is adapted to cooperate with a longitudinally reciprocable pin or plunger 55 slidably guided in a bore 56 in a bearing member 57. At its rearward end the pin 55 is pivotally connected at 58 with one end of a lever 59 whose opposite end is pivotally connected at 60 to a threaded member 61 which receives the forward end of a threaded rod 62. The forward portion of this rod is provided with an enlargement 63 forming a shoulder 64, and a spring 65 is compressed between a nut 66 cooperating with the threaded rearward end of the rod 62 and a collar 67 slidably mounted on the rearward reduced end of the rod 62 and normally engaging the shoulder 64. The enlarged forward end 63 of the rod 62 passes through a trunnion device 68 supported by a shipper member 69 pivotally mounted at 70 within a support element 71 carried within the feed frame. This lever 69 carries between the trunnion device 68 and the lever pivot 70 clutch applying elements 72, 72 which engage the rearward end surface of a clutch applying sleeve 73 slidably mounted on the tubular shaft 33, as shown in Fig. 3. It will be evident from the foregoing description that movement to the left of the rod 62 in Fig. 2 will result in the transmission of no pressure to the clutch shipper sleeve 73 until the sliding collar 67 engages the end of the trunnion device 68; but that further movement to the left, in this figure, of the rod 62 will thereafter impart a load to the shipper sleeve 73 which will be determined by the extent of the movement of the rod and the degree of compression of the spring 65. A movable fulcrum for the lever 59 is provided by an adjustable rod 74 pivotally connected at its forward end at 75 to the lever 59 between its pivotal connections 58 and 60, as shown in Fig. 2. This rod is guided within bearing members 76 and 77 within the feed frame and has threaded connected at its rearward end a nut member 78 for an operating handle 79. This nut member is held against axial displacement by means of a groove 80 thereon engaged by a flange 81 on the feed frame. The rod 74 also carries a collar 82 engageable with a lever arm of a pivoted shipper member 83 for operating the pressure plate 84 of the high speed clutch 38. Rotation of the nut member 78 in a direction to effect movement of the rod 74 toward the left in Fig. 2 moves the fulcrum 75 of the lever 59 toward the left, and thereby moves the pin 55 into engagement with the cam surface 54; and upon movement of the fulcrum sufficiently far to the left the other end of the lever 59 will have sufficient throw so that the shoulder 64 will pass inside the trunnion device 68 and permit the collar 67 to contact with the trunnion device and the spring 65 to load the low speed friction clutch 37. Obviously, when the spring 65 is under sufficient compression so that it will yield only when a pressure adequate to effect power transmission through the discs of the friction clutch 37 is applied to the collar 67, the adjustment of the lever fulcrum will effect rotation of the worm 39 at a low speed by the bevel gear 31 for any desired part of each revolution of the latter. When the rod 74 is moved to the left so far that the collar 67 continuously presses under the pressure of the spring against the trunnion device 68, continuous rota-

tion of the worm 39 will take place, the spring 65 will compress during each rotation of the bevel gear 31 an amount substantially equal to the full throw of the cam 54; but since the load 5 of the spring is desirably above the minimum necessary to effect power transmission through the friction clutch discs, there will be no release even when the lowest point in the cam 54 is opposite the pin 55. However, by moving the 10 fulcrum rod 74 graduated amounts toward the right in Fig. 2, the period of drive during each rotation of the bevel gears 31 may be progressively reduced until it is entirely discontinued. When the fulcrum rod 74 is moved a sufficient distance 15 toward the right in Fig. 2, the low speed clutch 37 is entirely released, and upon engagement of the collar 82 on the rod with the lever arm of the clutch shipper 83 the latter may be swung rearwardly to effect application of the high speed 20 clutch 38, and as a result the worm 39 is driven at a continuous high speed. It is therefore evident that by suitable adjustment of the fulcrum rod 74 the worm 39 may be driven at a continuous high speed, at a continuous low speed and 25 intermittently driven at a number of different still lower mean speeds. As a result, the feed operating and controlling drums 10 and 11 may be separately or simultaneously driven in a direction to wind in their respective cables and 30 under the control of the disc clutches 44 and 45 at variable low speeds between zero and a predetermined maximum low speed and at a relatively high predetermined speed.

In the form of the invention shown in Figs. 8 35 to 13, inclusive, there is shown keyed to the rear end of the motor power shaft 8, as shown in Fig. 9, a spur pinion 85 meshing with a spur gear 86 keyed to a longitudinally extending shaft 87 herein arranged parallel with and below the motor 40 power shaft and suitably journaled within the machine frame. Keyed to and driven by the shaft 87 is a bevel gear 88 meshing with a bevel gear 89 keyed to a vertical shaft 90 suitably journaled within the machine frame. Also keyed 45 to the shaft 90 and driven thereby is a spur gear 91 meshing with a spur gear 92 having its hub keyed at 93 to a vertical shaft 94 likewise suitably journaled within the machine frame. Journaled on the hub of the gear 92 by a bearing sleeve 95 50 is a chain sprocket 96 which engages and drives the cutter chain 5. The gear 92 is connectible to the chain sprocket 96 by a pinclutch 97 similar to the clutch 27 heretofore described and having similar operating means. Keyed to the upper 55 end of the shaft 94 is a bevel gear 98 meshing with a bevel gear 99, herein the high speed terminal gear. The hub of the gear 99 is keyed to the rear end of a longitudinally extending shaft 100 herein arranged with its axis parallel with 60 and above the motor shaft axis and likewise suitably journaled within the machine frame. Keyed to the forward end of the shaft 100 is a spur pinion 101 meshing with a spur gear 102 keyed to a longitudinally extending shaft 103 65 suitably journaled within the feed frame. Keyed to the shaft 103 and driven thereby is a spur pinion 104 meshing with a spur gear 105, herein the low speed terminal gear, suitably rotatably mounted on the shaft 103. Also rotatably mounted on the shaft 100 is a tubular shaft 106, and the gears 99 and 105 constituting the high and low speed driving elements, respectively, are connectible to this tubular shaft by multiple disc clutches 107 and 108. The operating means for these clutches will later be de-

scribed. Formed on the shaft 106 is a worm 109 meshing at its opposite sides with worm wheels 110 and 111 which are mounted and arranged to drive the feed operating and controlling drums in a manner disclosed in the preferred form of 5 the invention, and as shown in Fig. 4. The manner of mounting the worm wheels and the controlling means for connecting the drums to their respective worm wheels are shown in Fig. 10, and, as above mentioned, as this drum driving structure is similar to that disclosed in the preferred 10 form of the invention, further description thereof is thought unnecessary.

Now referring to the improved operating means for the high and low speed clutches 107, 108, respectively, and more particularly to the improved operating means for the low speed clutch, it will be noted that formed on the forward face of the spur gear 105 is a cam 115 with which is adapted 15 to engage a longitudinally reciprocable plunger or pin 116 guided in a bore 117 formed in a bearing member 118. The forward end of this plunger is pivotally connected at 119 with one end of a lever 120 whose opposite end is pivotally connected at 122 to a threaded member 123 which 20 receives the forward end of a threaded rod 124. The rearward end of the rod is provided with an enlargement 125 forming a shoulder 126, and a spring 127 is compressed between a nut 128 threaded on the rod and a collar 129 slidably 25 mounted upon the rod and normally engaging the shoulder 126. The enlarged rearward end of the rod 124 passes through a trunnion device 130 supported by a shipper member 131 pivotally mounted at 132 within the machine frame. This 30 shipper member carries at its opposite side from its pivots, clutch applying elements 133, 133 which engage a ball bearing shipper member 134 35 slidably mounted on the tubular shaft 106. It will be evident from the foregoing description 40 that movement to the right of the rod 124 in Fig. 8 will result in the transmission of no pressure to the clutch shipper member 134 until the sliding collar 129 engages the end of the trunnion device 130; but that further movement to the right, in 45 this figure, of the rod 124 will thereafter impart a load to the shipper member 134 which will be determined by the extent of the movement of the rod and the degree of compression of the spring 127. A movable fulcrum for the lever 50 120 is provided by a trunnion device 135 which is held upon a longitudinally movable rod 136 between a shoulder 137 on the latter and a collar 138 pinned to the rod. The rearward end of the longitudinally movable rod 136 is threadedly engaged at 139 within a boss 140 formed on the 55 rear end wall of the feed frame. Fixed to the rear end of the screw threaded rod is an operating handle 141 for rotating the screw to effect axial movement of the rod. Also fixed to the 60 rod 136 is a collar 142 engageable with a trunnion device 143 surrounding the rod and pivotally mounted in the outer end of a shipper member 144. This shipper member is pivotally mounted at 145 on the feed frame and carries clutch applying elements 146 engageable with a ball bearing clutch applying member 147 mounted on the tubular shaft 106, for applying the high speed clutch 107. Through the means above described, 65 rotation of the worm 109 may be effected at a continuous high speed or a continuous low speed, and intermittent rotation at a number of different still slower mean speeds. Rotation of the handle 141 in a direction to cause movement of the rod 136 toward the left in Fig. 8 results 70 75

in loading of the high speed friction controlling clutch 107 and driving of the worm 109 directly by the high speed terminal gear 99. Rotation of the handle 141 in a direction to effect movement of the rod toward the right in Fig. 8 moves the fulcrum 135 of the lever 120 toward the right and thereby moves the pin 116 into engagement with the cam 115; and upon movement of the fulcrum sufficiently far to the right, the other end of the lever 120 will have sufficient throw so that the shoulder 126 will pass inside the trunnion device 130 and permit the collar 129 to contact with the trunnion device and the spring 127 to load the low speed friction controlling clutch 108. Obviously, when the spring 127 is under sufficient compression so that it will yield only when a pressure adequate to effect power transmission through the discs of the friction clutch 108 is applied to the trunnion 130, the adjustment 20 of the fulcrum device 135 may effect rotation of the worm 109 at a low speed by the low speed terminal gear 105 for any desired part of each revolution of the latter. When the rod 136 is moved to the right so far that the collar 129 continuously presses, under the pressure of the spring, against the fulcrum device 125, continuous rotation of the worm 109 will take place and the spring 127 will compress during each rotation of the gear 105 an amount substantially equal to the full throw of the cam 115; but since the load of the spring is desirably above the minimum necessary to effect power transmission through the friction clutch discs, there will be no release, even when the lowest point in the cam 115 is opposite the pin 116. However, by moving the rod 136 graduated amounts toward the left in Fig. 8, the period of drive during each rotation of the gear 105 may be progressively reduced until it is entirely discontinued. It will thus be evident that the feed operating and controlling drums 10 and 11 may be driven in a direction to draw in their respective cables separately or simultaneously at variable low speeds and at a predetermined high speed under the control of the drum controlling clutches.

From the foregoing description the mode of operation of both forms of the improved feeding mechanism will be clearly apparent, and as the use of a room and pillar coal mining machine of 50 the type disclosed is well understood by those skilled in the art, a detail description of the general mode of operation of the machine is thought to be unnecessary. It will be noted, however, that the machine may be fed over the mine floor 55 at a relatively high haulage speed by either drum under the control of the high speed friction. The machine may also be fed at any desired low speed from its maximum low speed down to zero by proper adjustment of the fulcrum. Overloading will be prevented in the illustrative embodiments shown in the drawings by the presence of the spring 65 in the preferred form and the spring 127 in the modification. The machine may be sumped in and fed transversely across the 60 coal face in accordance with the room and pillar system of cutting, by means of the feed drum and under the control of the controlling drum.

As a result of this invention, it will be noted 70 that an improved mining machine feeding mechanism is provided which is of a rugged and compact character and which is particularly adapted to use in coal mining machines of the room and pillar type wherein at times substantial variations in the feeding speed are of importance. It 75 will further be noted that by arranging the fast

and slow speed drive trains and arranging the drum controlling clutches in the manner disclosed, a very convenient and simple operating mechanism for all of the clutches used in the control of the feed of the machine is made possible. It will further be noted that a continuous low feed and an intermittent low feed are both available by the same mechanism, permitting a wide variation in the feeding speeds attained, thereby to suit different cutting conditions. Further advantages will be apparent to those skilled in the art. 10

While there are in this application specifically described two forms which the invention may assume in practice, it will be understood that these forms of the same are shown for purposes of illustration and that the invention may be modified and embodied in various other forms without departing from its spirit or the scope of the appended claims. 20

What I claim as new and desire to secure by Letters Patent is:

1. In a mining machine, kerf cutting mechanism including a kerf cutter driving element disposed on a vertical axis, motor operated gearing for driving said element, and feeding means for the machine including a low speed gear train and a high speed gear train, said high and low speed gear trains driven through said gearing, said low speed gear train including a driving element co- 25 axial with said kerf cutter driving element, and said low speed gear train including a friction clutch, and means driven by an element of said low speed gearing as distinct from said high speed gearing for intermittently applying and 30 releasing said clutch at timed intervals. 35

2. In a mining machine, kerf cutting mechanism including a kerf cutter driving element disposed on a vertical axis, motor operated gearing for driving said element, and feeding means for the machine including a low speed gear train and a high speed gear train, the drive for the low and high speed gear trains including a driving element coaxial with said kerf cutter driving element, and said low speed gear train including 40 a friction clutch, and means driven by an element of said low speed gearing as distinct from said high speed gearing for intermittently applying and 45 releasing said clutch at timed intervals. 50

3. In a mining machine, kerf cutting mechanism, motor operated driving means for said kerf cutting mechanism including a cutter drive element disposed on a vertical axis, and feeding means for the mechanism including high and low speed gear trains, said low speed gear train driven through said cutter drive element, a horizontal shaft driven through said low speed gear train, said low speed gear train including a friction clutch coaxial with said horizontal shaft, and means driven through said vertical drive element for intermittently applying and releasing said clutch at timed intervals. 55

4. In a mining machine, kerf cutting mechanism, motor operated driving means for said kerf cutting mechanism including a cutter drive element disposed on a vertical axis, and feeding means for the machine including high and low speed gear trains driven through said vertical drive element, a horizontal shaft driven through 65 said low speed gear train, said low speed gear train including a clutch coaxial with said horizontal shaft, and means driven through said vertical drive element for intermittently applying and 70 releasing said clutch at timed intervals. 70

5. In a mining machine, kerf cutting mechanism including a kerf cutter driving element disposed on a vertical axis, a motor driven shaft for driving said cutter driving element, and feeding means for the machine including high and low speed gear trains driven by said motor driven shaft, said low speed gear train including a driving element coaxial with said kerf cutter driving element, a horizontal shaft driven through said 10 low speed gear train, said high and low speed gear trains including elements coaxial with said horizontal shaft, said low speed gear train including a friction clutch coaxial with said horizontal shaft, and means driven by power from 15 said motor driven shaft for intermittently applying and releasing said clutch at timed intervals.

6. In a mining machine, kerf cutting mechanism including a kerf cutter driving element disposed on a vertical axis, a motor driven shaft for driving said cutter driving element, and feeding means for the machine including high and low speed gear trains driven by said motor driven shaft and including a driving element coaxial with said kerf cutter driving element, a horizontal shaft driven by said low speed gear train, said high and low speed gear trains including elements coaxial with said horizontal shaft, said low speed gear train including a friction clutch coaxial with said horizontal shaft, and means 30 driven by power from said motor driven shaft for intermittently applying and releasing said clutch at timed intervals.

7. In a mining machine, kerf cutting mechanism including a kerf cutter driving element disposed on a vertical axis, a motor driven shaft for driving said cutter driving element, and feeding means for the machine including high and low speed gear trains driven by said motor driven shaft, said low speed gear train including a driving 40 element coaxial with said cutter driving element, a horizontal shaft driven by said low speed gear train, said high and low speed gear trains including elements coaxial with said horizontal shaft, said low speed gear train including a friction clutch coaxial with said horizontal shaft, and means driven by one of said elements coaxial with said horizontal shaft for intermittently applying and releasing said clutch at timed intervals.

50 8. In a mining machine, kerf cutting mechanism including a kerf cutter driving element disposed on a vertical axis, a motor driven shaft for driving said cutter driving element, and feeding means for the machine including high and low speed gear trains driven by said motor driven shaft, said high and low speed gear trains including a driving element coaxial with said cutter driving element, a horizontal shaft driven by said low speed gear train, said high and low speed gear trains including elements coaxial with said horizontal shaft, said low speed gear train including a friction clutch coaxial with said horizontal shaft, and means driven by one of said elements coaxial with said horizontal shaft for 65 intermittently applying and releasing said clutch at timed intervals.

9. In a mining machine, kerf cutting mechanism including a kerf cutter driving element disposed on a vertical axis, a motor driven shaft for driving said cutter driving element, and feeding means for the machine including a low speed gear train driven by said motor driven shaft and including a driving element coaxial with said cutter driving element, said low speed gear train including a friction clutch disposed on a horizontal 75

axis, and means driven by said motor driven shaft for intermittently applying and releasing said clutch at timed intervals.

10. In a mining machine, kerf cutting mechanism including a kerf cutter driving element disposed on a vertical axis, a motor driven shaft for driving said cutter driving element, and feeding means for the machine including a low speed gear train driven by an element coaxial with said cutter driving element, a horizontal shaft driven by 10 said low speed gear train, said low speed gear train including a friction clutch coaxial with said horizontal shaft, and means driven by said motor driven shaft for intermittently applying and releasing said clutch at timed intervals. 15

11. In a mining machine, kerf cutting mechanism including a kerf cutter driving element, motor operated driving means for said kerf cutting mechanism including a shaft extending longitudinally of the machine and operatively connected to said kerf cutter driving element to drive the latter, and feeding means for the machine including a shaft arranged coaxially with said longitudinal shaft, a low speed gear train driven by said longitudinal shaft including a gear coaxial 20 and rotatable with said kerf cutter driving element, a low speed clutch for connecting said shafts in driving relation through said gear train, and mechanism operated by an element of said low speed gear train for intermittently applying 25 and releasing said clutch at timed intervals.

12. In a mining machine, kerf cutting mechanism including a kerf cutter driving element, motor operated driving means for said kerf cutting mechanism including a shaft extending longitudinally of the machine and operatively connected to said kerf cutter driving element to drive the latter, and feeding means for the machine including a shaft arranged coaxially with said longitudinal shaft, a low speed gear train driven by 30 said longitudinal shaft including a gear coaxial and rotatable with said kerf cutter driving element, a low speed clutch for connecting said shafts in driving relation through said gear train, mechanism operated by an element of said low speed gear train for intermittently applying and 35 releasing said clutch at timed intervals, and a high speed gear train driven through said shaft extending longitudinally of the machine and operatively connected to said kerf cutter driving 40 element.

13. In a mining machine, kerf cutting mechanism including a kerf cutter driving element, motor operated driving means for said kerf cutting mechanism including a shaft extending longitudinally of the machine and operatively connected to said kerf cutter driving element to drive the latter, and feeding means for the machine including a shaft arranged coaxially with said longitudinal shaft, a low speed gear train driven by 50 said longitudinal shaft including a gear coaxial and rotatable with said kerf cutter driving element, a low speed clutch for connecting said shafts in driving relation through said gear train, mechanism operated by an element of said low speed gear train for intermittently applying and 55 releasing said clutch at timed intervals, and a high speed gear train driven through said shaft extending longitudinally of the machine and operatively connected to said kerf cutter driving 60 element and including a high speed gear coaxial with said longitudinal shaft.

14. In a mining machine, kerf cutting mechanism including a kerf cutter driving sprocket, motor operated driving means for said sprocket 70

including a gear coaxial and rotatable with said sprocket, and feeding means for the machine including a high speed gear train and a low speed gear train, said gear trains respectively including 5 high and low speed terminal gears arranged on axes extending longitudinally of the machine and said low speed gear train driven by said coaxial sprocket driving gear, a clutch controlling the drive by said low speed terminal gear, and means 10 actuated by an element of said low speed gear train for automatically applying and releasing said clutch at timed intervals.

15. In a mining machine, kerf cutting mechanism including a kerf cutter driving sprocket, 15 motor operated driving means for said sprocket including a gear coaxial and rotatable with said sprocket, and feeding means for the machine including a high speed gear train and a low speed gear train, said gear trains respectively including 20 high and low speed terminal gears arranged on axes extending longitudinally of the machine and both gear trains driven by said coaxial sprocket driving gear.

16. In a mining machine, kerf cutting mechanism including a kerf cutter driving sprocket, 25 motor operated driving means for said sprocket including a gear coaxial with said sprocket, and feeding means for the machine including a low speed gear train, said gear train including a bevel 30 gear coaxial with said sprocket driving gear and driven thereby, a bevel gear meshing with and driven by said coaxial bevel gear, a horizontal shaft arranged coaxially with and driven by said last mentioned bevel gear, a clutch for connecting 35 said last mentioned bevel gear to said shaft, and means actuated by an element of said low speed gear train for automatically applying and releasing said clutch at timed intervals.

17. In a mining machine, kerf cutting mechanism including a kerf cutter driving sprocket, 40 motor operated driving means for said sprocket including a gear coaxial with said sprocket, and feeding means for the machine including a high speed gear train and a low speed gear train, said 45 low speed gear train including a bevel gear coaxial with said sprocket driving gear and driven thereby, a bevel gear meshing with and driven by said coaxial bevel gear, and a horizontal shaft arranged coaxially with and driven by said 50 last mentioned bevel gear and said low speed gear train including a clutch for connecting said last mentioned bevel gear to said shaft, and means actuated by an element of said low speed gear train for automatically applying and releasing 55 said clutch at timed intervals, said gear trains driving said horizontal shaft selectively at continuous high and intermittent low speeds.

18. In a mining machine, kerf cutting mechanism including a kerf cutter driving element, 60 motor operated driving means for said kerf cutting mechanism including a shaft extending longitudinally of the machine, a parallel shaft operatively connected to said kerf cutter driving element and gearing connecting said shafts in 65 driving relation, and feeding means for the machine including a driven shaft coaxial with and rotatable relative to said first mentioned longitudinal shaft, a low speed gear train including a gear coaxial and rotatable with said kerf cutter driving element, and a low speed terminal 70 driving gear coaxial with said coaxial driven shaft, a clutch for connecting said low speed terminal gear to said coaxial driven shaft, and means actuated by said low speed terminal gear 75

for intermittently applying and releasing said clutch at timed intervals.

19. In a mining machine, kerf cutting mechanism including a kerf cutter driving element, 5 motor operated driving means for said kerf cutting mechanism including a shaft extending longitudinally of the machine, a parallel shaft operatively connected to said kerf cutter driving element and gearing connecting said shafts in 10 driving relation, and feeding means for the machine including a driven shaft coaxial with and rotatable relative to said first mentioned longitudinal shaft, a low speed gear train including a gear coaxial and rotatable with said kerf cutter driving element and a low speed terminal 15 driving gear coaxial with said coaxial driven shaft, a clutch for connecting said low speed terminal gear to said coaxial driven shaft, means actuated by said low speed terminal gear for intermittently applying and releasing said clutch 20 at timed intervals, and a high speed gear train including a gear coaxial with and driven by said parallel shaft and a high speed terminal gear coaxial with said coaxial driven shaft, and a clutch 25 for connecting said high speed terminal gear to said coaxial driven shaft.

20. In a mining machine, kerf cutting mechanism including a kerf cutter driving element, 30 motor operated driving means for said kerf cutting mechanism including a gear coaxial with 35 said kerf cutter driving element for driving the latter, and feeding means for the machine including a horizontal driven shaft extending longitudinally of the machine, a high speed gear train including a gear coaxial with and driven by 40 said cutter driving element driving gear and a high speed terminal gear coaxial with said shaft, a clutch for connecting said high speed terminal gear to said shaft, a low speed gear train driven by said gear coaxial with said cutter driving element driving gear including a shaft coaxial with 45 said longitudinal shaft, a low speed terminal gear coaxial with and driven by said coaxial shaft, a clutch for connecting said low speed terminal gear to said longitudinal driven shaft, and means actuated by an element of the low speed gear train for intermittently applying and releasing 50 said low speed clutch at timed intervals.

21. In a mining machine, kerf cutting mechanism including a kerf cutter driving sprocket, 50 motor operated driving means for said sprocket including a gear coaxial and rotatable with said sprocket, and feeding means for the machine including a high speed gear train and a low speed gear train, said low speed gear train driven by 55 said coaxial sprocket driving gear and said gear trains including high and low speed clutches arranged in coaxial relation on horizontal axes, and means driven through said coaxial sprocket driving gear for intermittently applying and releasing 60 said low speed clutch at timed intervals.

22. In a mining machine, kerf cutting mechanism including a kerf cutter driving sprocket, 65 motor operated driving means for said sprocket including a gear coaxial and rotatable with said sprocket, and feeding means for the machine including a high speed gear train and a low speed gear train, said gear trains both driven by said coaxial sprocket driving gear and including high and low speed clutches arranged in coaxial 70 relation on horizontal axes, and means driven by said coaxial sprocket driving gear for intermittently applying and releasing said low speed clutch at timed intervals.
